(57) **CLAIM**

The ornamental design for a pivot connector, as shown and described.

DESCRIPTION

FIG. 1 is a front right perspective view of a pivot connector, in a straight orientation, according to our new design; FIG. 2 is a front view thereof, in a straight orientation; FIG. 3 is a rear view thereof, in a straight orientation; FIG. 4 is a right side view thereof, in a straight orientation; FIG. 5 is a left side view thereof, in a straight orientation; FIG. 6 is a top view thereof, in a straight orientation; FIG. 7 is a bottom view thereof, in a straight orientation; FIG. 8 is a front right perspective view thereof, in a bent orientation; FIG. 9 is a front view thereof, in a bent orientation; FIG. 10 is a rear view thereof, in a bent orientation; FIG. 11 is a right side view thereof, in a bent orientation; FIG. 12 is a left side view thereof, in a bent orientation; FIG. 13 is a top view thereof, in a bent orientation; and, FIG. 14 is a bottom view thereof, in a bent orientation. The broken lines illustrate portions of the pivot connector and form no part of the claimed design.

1 Claim, 12 Drawing Sheets
